GAS BURNER

Adolf J. Burklin, Toledo, Ohio, assignor to The Burkay Company, Toledo, Ohio, a corporation of Ohio

Application August 12, 1937, Serial No. 158,742

9 Claims. (Cl. 158—104)

This invention relates to gas burners of the type intended more particularly for use in connection with water heaters.

An object of the invention is the provision 5 of a burner of this character of simple and efficient construction and adapted to provide a supplemental supply of heated air and to direct its discharge into the flame rising from the burner when burning, whereby to support combustion of practically all carbon matter in the flame and produce a flame of maximum efficiency.

A further object of the invention is the provision of a ring type burner of this character 15 having a novel and compact arrangement of gas supply manifold, air and gas mixing tubes and supplemental air discharge means, whereby to enhance the efficiency and commercial value thereof.

20 Further objects and advantages of the invention will be apparent from the following detailed description and from the accompanying drawing, in which—

Figure 1 is a side elevation of a burner embodying the invention; Fig. 2 is a top plan view thereof; Fig. 3 is an enlarged section of the burner on the line 3—3 in Fig. 2; Fig. 4 is an enlarged sectional view of a burner spud used in connection with the burner manifold, and Fig. 5 30 is a fragmentary section on the line 5—5 in Fig. 3.

The burner comprising the invention includes in its preferred embodiment a gas manifold section A, a mixer section B and a supplemental air supply section C.

The manifold section A comprises a ring form of manifold having an inlet passage 2 at one side, a cleanout passage 3 at its opposite side closed by a removable plug 4, and has on its 40 under side a plurality of lugs or bosses forming supporting feet. The ring 1 is provided on its top with a substantially flat seat 5 which is tapped at equidistantly spaced points there-around to receive burner spuds 6 opening into the interior of the ring and having their upper headed ends projecting a distance above the seat 5, as shown. These spuds are adapted to register with and correspond in number to the mixing tubes in the mixer section.

50 The mixer section B is of ring form of a diameter to seat down on the manifold seat 5 and includes an annular series of vertically disposed mixer tubes 10 joined at their sides by webs 11 and each seating at its lower end on said manifold seat around the head of a respective burner

spud 6, which serves to center the mixer section on the manifold. Each tube 10 has the lower end portion of its bore reduced to receive and mount the lower end of a smaller mixer tube 12 with its upper portion spaced from the wall of the tube 10 to provide an annular space 13 therebetween.

The tube 10 has a cross-bore 14 below the tube 12 for admitting the primary mixture of air to the latter and is provided with a larger cross-bore 15 through the lower end portion of the 10 space 13 to admit a secondary mixture of air to said space and to the large bore of the tube 10. It is thus apparent that each tube 10 and 12 is of the double tube Bunsen burner type wherein there is first a primary mixing and then a secondary mixing of air with the gas discharged into the mixer tube from the burner space, as well understood in the art.

The tubes 10 at their upper ends are connected by and preferably formed integral with a top 20 ring 16 which is vertically bored to form open top continuations of the tube bores with the upper ends of such bores outwardly flared, as at 17. The inner side wall of the ring 16 is preferably inwardly and upwardly tapered and continues a 25 short distance above the open upper end of the ring bore and forms an inturned horizontal flange 18.

The supplemental air supply section C seats on the flange 18 in spaced overhanging relation to the tubes 10 and forms an air chamber 20 having supply communication through its bottom and through the opening 19 of said flange with the air space within the mixer section B. The discharge outlet from the chamber 20 is in the 35 form of an annular slot 21 through its circumferential wall and disposed substantially radially of the chamber. It is thus apparent that the supplemental air discharge is in annular film form crosswise of and in commingling relation 40 to the flame and unburned combustible material rising from the mixer section around the edge of the section C.

The section C embodies in the present instance a bottom plate 22 and top plate 23 held 45 by spacer blocks 24 in proper spaced relation to form the discharge slot 21, and are secured together by screws 25 passing through the plate and blocks and threaded into the flange 18 to hold the sections B and C centered.

The bottom plate 22 is of ring form with its opening registering with that of the flange 18, and its outer edge portion is raised to form an upstanding wall with the upper edge of such wall radially flanged or broadened as shown at 50 55

26. The outer bottom edge portion of the plate 22 extends over the upper open end of the mixer tube 10 in spaced relation thereto and terminates at substantially the outer edge of the ring 16 5 to form the radially opening flame discharge slot 21, as shown, with the top edge flange 26 projecting out somewhat further and in greater vertically spaced relation to the tube opening.

The top plate 23 is preferably slightly larger 10 in diameter than the bottom plate 22 with its under side seated to form a downturned edge flange 28 which is concentric to and vertically spaced from the flange 26 to provide the annular air discharge slot 21 therebetween. The plate 15 23 is preferably further upwardly dished at its central portion to increase the capacity of the air chamber 20 formed by the two plates 22, 23. A bolt 30 passes centrally through the top plate 23 and thence down the central open part of 20 the burner and through a central aperture in a spider or frame part 31 disposed within the manifold ring 1 and forming a part thereof. This bolt serves to hold the manifold section A in assembled relation to the other sections B 25 and C with the bottom edge of the section B properly seated on the manifold top 5.

When the burner is in use with the supply 30 of gas in the manifold 1 open and with the flame discharging in annular sheet form from the flame block 21, it is apparent that the flame will pass up around the outer edge of the supplemental air supply section C and effect a heating of the lower wall of such section and will also heat the interior wall of the mixer section C. The 35 air for the supplemental chamber 20 passes up through the interior of the mixer section B thereby becoming partially heated by the mixer section and is further heated within the chamber 20 by radiation from the walls of such chamber. This heated air is then discharged from the 40 chamber 20 in annular sheet form into the burner flame and effects a complete combustion of the unburned carbon particles contained in the flame, thus producing an intensely hot flame.

I wish it understood that my invention is not 45 limited to any specific construction, arrangement or form of the parts, as it is capable of numerous modifications and changes without departing from the spirit of the claims.

Having thus described my invention, what I 50 claim as new, and desire to secure by United States Letters Patent, is:

1. A gas burner comprising a gas supply manifold of ring form having an annular series of 55 burner spuds on its top, an annular mixer section mounted on said manifold and having mixer tubes in register at their bottoms with said spuds, said tubes being joined at their sides to cooperate therewith to form an air passage upward through 60 the central portion of the mixer section, said mixer section having an inturned flange at its top, a supplemental air discharge section mounted on said flange concentric to the mixer section and forming an air chamber in communication 65 through said flange with a source of air supply through the central portion of the mixer section, and having its outer edge overhanging the upper ends of the tubes of said mixer section to cooperate therewith to form a lateral flame discharge slot and itself having a lateral air discharge slot 70 above said flame discharge slot.

2. In a gas burner comprising a gas supply manifold with an annular series of burner spuds on its top, a ring form of burner section mounted 75 on said manifold and having mixer tubes in

register with said spuds, a supplemental air discharge section mounted on the top of said mixer section and having spaced bottom and top plates cooperating to form an air chamber, and a lateral air discharge slot around the side edge of said 5 chamber, said lower plate overhanging the upper ends of the mixer tubes of said mixer section and cooperating therewith to form a lateral flame discharge slot below said air discharge slot, said air chamber being in communication with and receiving its air supply through the space within 10 said mixer ring.

3. A gas burner comprising a gas supply manifold section of ring form having an annular series of burner spuds in its top, a ring form of mixture 15 section mounted on said manifold section and having an annular series of mixer tubes in register with said spuds, and a supplemental air discharge section mounted on the top of said mixer section and overhanging the mixer tubes of the 20 mixer section to laterally deflect and be heated by a flame rising from said mixer section, said air discharge section having an air chamber in air supply communication with the interior of the mixer section through its top and having an annular side discharge slot for directing a stream 25 of air laterally into a flame rising from said mixer section.

4. A gas burner comprising a gas supply manifold section of ring form with an annular series 30 of burner spuds in its top, a mixer section comprising an annular series of mixer tubes mounted on the manifold section in register with said spuds and having connecting webs therebetween, said mixer section also having at its upper inner 35 edge an annular flange forming a center opening in communication with the interior space of the mixer section, a supplemental air discharge section mounted on said flange and forming an air chamber with its bottom open to said flange 40 opening to receive air therethrough and having its side edge provided with an annular slot for discharging air laterally into a flame rising from the mixer section, said air section having its bottom overhanging the upper, outer edge portion 45 of the mixer section in spaced relation thereto to outwardly deflect the mixture discharging from said mixer tubes, and means securing the sections in assembled relation.

5. A gas burner comprising a gas supply manifold having a series of gas discharge orifices in 50 its top arranged around a common point, a mixer section mounted on said manifold and having mixer tubes in register at their lower ends with said orifices and having their upper 55 ends open, said section having an air passage upward therethrough, a hollow supplemental air discharge section mounted on the top of said mixer section in overhanging relation to the open upper ends of said tubes and cooperating with the 60 mixer section to effect a laterally directed mixture discharge from said tubes, said air discharge section receiving its air supply from said air passage and having provision at its side edge to 65 direct air laterally into the burning mixture discharging from said mixer section.

6. A gas burner having an endless gas supply manifold with a series of gas discharge orifices in its top, an endless mixer section mounted on said manifold and having a series of mixer 70 tubes in register at their lower ends with said orifices with their upper ends open, said tubes having their sides connected to combine to form an air passage upward through the mixer section, a deflector plate mounted on the upper end 75

of the mixer section in overhanging vertically spaced relation to the open ends of said tubes to cooperate therewith to discharge a mixture laterally from the upper ends of the tubes, a top plate mounted over said deflector plate to cooperate therewith to form a hollow air chamber with provision at the side edge for discharging air laterally into the burning mixture rising from said tubes around said deflector plate, said air chamber having communication at its bottom with the interior air space of the mixing section.

5 7. A gas burner comprising a ring form of gas supply manifold section with a series of gas discharge orifices in its top, a mixer section seated on the manifold section and having a series of 15 mixer tubes in register with said orifices with their upper ends open, said mixer section forming an interior air space open at its lower end, and a supplemental air discharge section mounted 20 over the mixer section in overhanging relation to the upper open ends of said tubes and cooperating therewith to effect a lateral mixture discharge, said supplemental section forming a chamber in communication through its bottom with said air 25 space and having provision at its side edge to discharge air laterally into the mixture discharging from said mixer section.

8. A gas burner comprising a gas supply section, a mixer section, a hollow supplemental air discharge section mounted in successive order 30 one on top of another, said mixer section having

a plurality of mixer tubes arranged around a common point, being open at their tops, and receiving their gas supply from said supply section and cooperating to form an air passage upward through the mixer section, said air discharge section overhanging the upper open ends 5 of said mixer section tubes and cooperating therewith to discharge the gas mixture laterally therefrom, said air section also having provision to take its air supply from said passage and 10 also having provision around its side edge for discharging air laterally into the gas mixture discharging from the mixer section.

9. A gas burner comprising a gas supply manifold of ring form having an annular series of 15 gas discharge orifices in its top, a ring form of mixer section mounted on said manifold and having an annular series of mixer tubes in register at their lower ends with said orifices and having their upper ends open, a hollow supplemental 20 air discharge section mounted on said mixer section and cooperating with the upper open ends of said mixer tubes to effect a lateral discharge of mixture therefrom, said air discharge section having its interior in communication with a 25 source of air supply through the mixer section and having provision at its side edge for discharging air laterally therefrom into the burning mixture rising from said mixer section.
